UNITED STATES PATENT OFFICE.

CHARLES V. STUART, OF MEMPHIS, TENNESSEE, ASSIGNOR TO STUART AMERICAN PRODUCTS COMPANY, OF MEMPHIS, TENNESSEE, A CORPORATION OF TENNESSEE.

SPRAY-BURNER.

1,164,140.

Specification of Letters Patent. Patented Dec. 14, 1915.

Application filed March 20, 1914. Serial No. 825,975.

To all whom it may concern:

Be it known that I, CHARLES V. STUART, a citizen of the United States, residing at Memphis, in the county of Shelby and State 5 of Tennessee, have invented certain new and useful Improvements in Spray-Burners, of which the following is a specification.

My present invention relates to a spray 10 burner, and provides means for atomizing and gasifying a mixture of air and oil prior to the point of combustion, such point being located within an elongated combustion chamber, the apparatus producing a result 15 closely approaching perfect combustion of the mixture.

The apparatus involves the admixing of air and hydro-carbon under pressure and subjecting it to successive compression and 20 expansion actions, the expansion immediately following the greatest compression, preferably in the presence of heat, expansion taking place within a combustion chamber which permits rapid action.

25 The preliminary admixture of the air and hydro-carbon is preferably provided in advance of the compression step, in any of several ways, the preferred manner being by forming what may be considered a 30 stream of the combined air and hydro-carbon and giving the stream a whirling action to deliver the combined mixture to a screen baffle in a direction angular to the face of the baffle and to the baffle axis. The baffle 35 being located at the entrance to the compression chamber, the direction of stream delivery relative to the baffle is such that the stream is directed at an angle against the baffle, and the result is a breaking up and 40 more complete admixture of the combined air and hydro-carbons, this admixture being immediately compressed and then expanded in the presence of heat. The whirling action is imparted by the use of a spiral 45 within a tube, the combined air and hydro-carbon being forced around the spiral by the pressure behind it.

The hydro-carbon employed may be more or less volatile as desired, the particular 50 apparatus permitting of the use of either the light or heavy oils more highly refined.

The drawing accompanying this application shows one form of an apparatus.

In said drawing, Figure 1 is a plan view,

and Fig. 2 is a sectional view taken on line 55 2—2 of Fig. 1.

Referring to the drawings, 1 indicates a burner tube provided with an hydro-carbon (indicated generally as oil) inlet 2 and an air inlet 3. Near the other end of the 60 tube is located a spiral 4, and between the spiral and the oil and air inlets is located a pressure-providing means such as a fan blower 5 adapted to force the combination 65 of the oil and air around the convolutions of the spiral 4. The exit end of the spiral is preferably located at the entrance to a compression chamber 7, the wall of which is preferably cone-shaped with an opening 8 at the smaller end of the chamber, the 70 latter being formed somewhat similar to a truncated cone, this chamber being preferably located at the end 6 of the tube 1. If desired, and I preferably employ the same, I may provide a screen baffle 10 at the entrance 75 to the compression chamber, the face of this baffle extending at right angles to the axis of the chamber 7, this baffle being also located at the exit end of the spiral, the result being that the combined air and oil 80 which is given a whirling action in being forced around the spiral convolutions is directed toward this screen baffle 10 in a direction angular both to the baffle face and the baffle axis; consequently, the stream of air 85 and oil not only has its direction of flow changed from the spiral to one approaching the direction of the axis of the chamber 7, but this change is made through the baffle 90 10, the direction of flow toward the baffle 95 tending to break up and atomize the stream and thus form a more intimate admixture of the combined air and oil immediately preceding its compression.

An enlarged, and preferably elongated 95 combustion chamber 9 having a constant diameter, surrounds the end 6 of the tube and may be attached thereto in any convenient manner. Said chamber 9 may be of any appropriate material which will not be 100 greatly affected by intense heat, and may be lined with asbestos, fire-clay or other fire-resisting material. As will be seen the combustion chamber is open at its forward end to permit of the passage of the flame outwardly, the burning of the admixture taking place within the combustion chamber. 110 This combustion has the effect of heating

the walls of the chamber, and the intense heat, being at the point of expansion, causes a more rapid gasifying action, so that the gaseous product is in such a state as to provide for substantially perfect combustion, the flame resultant therefrom providing an intense heat upon its issuance from the combustion chamber. In this connection, the relative sizes of the parts become of some importance, the diameter of the combustion chamber being preferably about double that of the tube 1 and about four or five times that of the restricted exit opening 8.

The general operation of the structure shown in the drawing appears obvious. The hydro-carbon enters through the inlet 2, preferably under a pressure sufficient to cause it to be introduced into the tube in the rear of the fan which also draws in air through the inlet 3. The air takes up the hydro-carbon and the combination is forced into the spiral passage under the pressure provided by the rotation of the fan, this pressure, after the fan has reached the desired speed, remaining constant and causing a constant supply to the spiral passageway. After traversing this passageway, within which there may be an atomizing effect, due to the form of the spiral, the combined air and hydro-carbon passes through the baffle 10 into the compression chamber 7 from which it is discharged through the restricted opening 8, into the combustion chamber 9. As will be understood, the compressed mixture, being under the pressure of the stream-like constant supply will be forced through the opening at an increased velocity, which is immediately and suddenly reduced by the expansion which at once follows the discharge through the restricted opening. This action causes the combined elements to more nearly approach complete atomization and gasification, the obtaining of this result being aided by the heat of the combustion chamber, producing an admixture which is highly inflammable. As this state is reached in proximity to the opening 8, it will be readily understood that the combustion takes place practically entirely within the combustion chamber. Furthermore, the usual reverberation is eliminated.

It will be obvious that, while I have shown a preferred embodiment of my invention, various modifications thereof will be sug-

gested to those skilled in the art to which the invention appertains. Such modifications and changes as may be required or desired in carrying out the principles of my invention are reserved, in so far as the same may fall within the spirit and scope of the invention as expressed in the accompanying claims.

What I claim as new is:

1. An apparatus of the class described comprising a conduit, means for inducing a current of air and oil into said conduit and for positively causing the mixture to pass along said conduit, a spiral in the path of travel of said mixture, and a screen baffle immediately adjacent the discharge end of said spiral, whereby the mixture may be forced around the convolutions of the spiral and delivered against the baffle at an angle to the axis thereof.

2. An apparatus of the class described comprising a conduit having a restricted exit, means for inducing a current of air and oil into said conduit and for forcing it through said exit, a spiral extending longitudinally of said conduit and a screen baffle immediately adjacent the discharge end of said spiral and in front of said exit, whereby the mixture is caused to pass around the convolutions of the spiral and delivered against the baffle at an angle to the axis thereof, prior to its passage through said exit.

3. An apparatus of the class described comprising a conduit provided with a conically shaped terminal having a restricted exit, an elongated cylindrical combustion chamber into which said terminal extends, a spiral in said conduit, a screen baffle immediately adjacent the discharge end of said spiral, and means for inducing a mixture of air and oil into said conduit and for forcing it around the convolutions of the spiral, against the baffle at an angle to the axis thereof, and through said exit into said combustion chamber to the point of combustion.

In testimony whereof I affix my signature in presence of two witnesses.

CHARLES V. STUART.
